UNITED STATES PATENT OFFICE.

EARL D. WRIGHT, OF SOUTH CHICAGO, ILLINOIS.

REHEATING CONTINUOUS FURNACE HEARTH.

Application filed November 6, 1928. Serial No. 146,669.

My invention relates to a furnace hearth for use in continuous reheating furnaces used in the reheating of steel billets prior to the rolling thereof into shapes and has particular reference to a hearth construction in which the temperature of the billets is maintained as evenly as possible throughout the entire billet, even though it is supported on the hearth during a part of the time required for the reheating of the billet.

A further object of my invention is the provision of a hearth having a billet discharge arrangement associated therewith so that the heated billets as they are discharged from the furnace have their temperature maintained and are uniformly heated throughout before being discharged from the furnace.

Another and further object of my invention is the provision of a furnace hearth of smooth and continuous construction over which steel billets can be passed without interrupting the passage of the billets or unnecessarily lowering the temperature of the billets as they pass over the hearth.

In continuous reheating furnaces it has been the practice to charge the furnace at one side thereof with the billets and to push the billets across skids arranged in longitudinal relation with the furnace and in spaced parallel relation with each other, through which water is kept continuously flowing in order that the skids may not be burned out of the furnace, these skids forming supporting members for the billets as they pass through a large part of the furnace. The skids being in contact with the billets prevent the billets on the side thereof which rests upon the skid from being

heated to the same degree as other parts of the billet, with the result that a certain area of each billet which is in contact with the skid is not heated to the same temperature as the balance of the billet. The practice is to push the billets onto a hearth provided in the furnace for the purpose of enabling the entire billet to become uniformly heated before it is discharged from the heating furnace. These hearths have been made of magnesite brick which in time become misplaced, presenting a rough and uneven surface over which the billets must pass retarding their passage and taking the heat therefrom. It is the usual practice to provide a trough at one side of the hearth, usually water-cooled, for the purpose of receiving the billets and

from which the billets are discharged by a pusher apparatus directly into the roll pass, but this practice is objectionable because the temperature of the billet is reduced too much. The billets cannot be discharged directly from the hearth because the friction of the billet passing over the surface of the hearth would soon wear the hearth to such a degree that the operation of the furnace would be interrupted until it could be repaired.

In my improved construction, these difficulties are overcome and means are provided comprising a pair of steel billets embedded in a sandstone hearth placed in spaced relation parallel with each other, upon which the billets rest as they are discharged from the furnace, these billets of course, being heated and the billets resting thereon will be of substantially the same heat as the billets comprising the discharge means, so that when a billet is discharged from the heating furnace it is substantially uniformly heated throughout. The cooler areas formed by the contact of the billets upon the water-cooled skids have become heated, which is necessary because if these areas are not heated the rolling operation cannot be successfully performed. It is, of course, well known that cold steel under roll pressure expands laterally, while hot steel is elongated by the pressure of the rolls and therefore, unless these billets are substantially uniform when they enter the rolls, irregular shapes will be turned out from the rolls.

These and other objects of my invention will be more fully and better understood by reference to the accompanying sheets of drawings in which:

Figure 1 is a longitudinal, vertical sectional view of a heating furnace equipped with my improved invention;

Figure 2 is a top plan view of the hearth of the heating furnace;

Figure 3 is a vertical sectional view illustrating the discharge means provided in the furnace hearth; and

Figure 4 is a detailed view in perspective showing the manner of securing the discharge members onto the furnace hearth.

Referring now specifically to the drawings, a heating furnace is shown having the usual foundations 10, with end walls 11 and 12, with a plurality of vertical side buckstays 13, 13 being provided which perform the function of supporting the side walls

of the furnace, and also to support a roof 14 which is the usual curved suspended form. A gas inlet 15 is provided with an air passage 16 also being provided, through which 5 air enters the furnace and becomes mixed with the gas entering through the passage 15 and passes up over a bridge wall 17 extending transversely across the furnace adjacent the discharge end of the furnace and 10 over which the flames pass toward the receiving end of the heating furnace as the air and gas are consumed by the combustion thereof in the furnace. A receiving opening 18 is provided at one end of the 15 furnace through which the billets are charged into the heating furnace, with a plurality of spaced skids 19 extending longitudinally of the furnace and having their outer ends curved downward beyond the 20 outer wall of the furnace and their inner ends terminating adjacent the hearth of the furnace and turning downward into a water discharge pipe 20, these pipes or skids having water constantly flowing therethrough 25 in order to preserve the skids, which form supports upon which the billets rest as they are forced through the furnace.

A hearth 21 is provided which is supported by a plurality of transversely extending 30 eyebeams 22, 22, the said hearth extending from a point adjacent the termination of the skids 19, 19 to the lower side of the bridge wall 17. The hearth in my improved 35 construction is made up of a plurality of rectangular shaped sandstone slabs 23, 23 and 23^a, 23^a, placed in two sets, each set being placed in end to end relation with each other, the slabs in each set being in edge to edge relation with each other, this hearth 40 being heated and receiving the billets as they are forced from the skids 19 through the heating furnace, and is provided for the purpose of enabling the billets to become uniformly heated after they pass over the 45 water-cooled skids 19, 19. A discharge door 24 is provided at one side of the furnace through which the billets are discharged from the heating furnace by a mechanical pusher, not shown, and which is in common 50 use in heating furnaces of this type, the discharge door being at the end of a runway formed by a pair of skids 25 and 26, these skids being formed of steel billets having their upper surface curved and extending 55 above the level of the hearth 21 for a slight distance and adapted to receive the billets as they are forced through the heating furnace and over which the billets are discharged by the combined action of the 60 pusher and the rolls.

The skid 25 is supported by a plurality of vertically extending posts 27, 27, these posts being spaced a suitable distance to support the skid 25, preferably with a post at each 65 end of the skid and for the ordinary type

of heating furnace with an intermediate post placed half way between the two end posts, although this arrangement may be altered if desired. The skid 26 is also supported by a plurality of posts 28, 28, these 70 posts being placed in spaced relation with each other and opposite the posts 27, 27 supporting the skid 25 so that the skid 26 is supported upon these posts and a spaced runway is formed over which the billets are 75 discharged through the discharge door 24 in the side of the furnace. One of the posts 28 is illustrated in detail in Figure 4 and comprises a rectangular shaped billet having a V-shaped recess 29 in the upper end thereof with a hole 30 extending through one side of the post through which a bolt 31 extends. The bolt 31 has a feather-key 32 in a key-way 33' formed in the lower end of the bolt 31, the skid 26 also having a diagonally extending hole 34 therethrough in register with the hole 30 in the post 28, with a counter-sunk recess 35 in the upper side thereof within which the head of the bolt 31 is adapted to seat. The lower end of the posts 80 28 has a rod 36 extending transversely therethrough with eyebolts 37 and 38 secured to the bolt 36 and extending through the supporting plate at the bottom of the hearth with ordinary nuts on the ends of the eyebolts so that the posts 28 can be drawn down tightly in position and supported by the bottom plate of the hearth. Each of these posts 28 is constructed in the manner heretofore described and the posts 27 are 85 also constructed in precisely the same manner, except that the holes through the skid 25 extend in an outward direction with bolts passing through the members 25 and feather-keys in the outer side thereof in 90 precisely the same manner except that they extend in directions opposite to the bolts 31. It will be understood, of course, that these skids 25 and 26 become heated to substantially the same temperature as the billets and that as these skids become heated they expand and the expansion draws the structure together very tightly, and that the structure also yields in a plurality of 95 places when cooled, due to a slight relative movement of the skids and posts and the eyebolts, so that while a slight amount of expansion and contraction is permissible when the device is heated, the entire structure expands so that it practically becomes 100 a unitary structure.

Should the skids 25 and 26 become worn they can easily be removed and replaced with new skids without an unusual delay in the operation of the furnace or without tearing down the structure of the furnace in order to replace the skids. V-shaped recesses are also formed in the hearth blocks 23, 23^a adapted to receive the skids 25 and 26 so that, as heretofore explained, these 105 110 115 120 125 130

skids fit into the hearth transversely thereof with their curved upper surfaces extended a slight distance above the surface of the hearth and forming skids or a runway over which the billets are discharged from the furnace.

In the operation of the device it will be understood that the billets are fed into the furnace through the opening 18 by means of 10 a mechanical pusher, not shown, and which is in common use in the operation of these heating furnaces, these billets being fed into the furnace transversely of the skids 19 and lying thereon during the initial heating 15 thereof, it being understood that the billets are fed into the furnace one at a time and the front billets pushed across the heating furnace in a step by step operation as other billets are fed into the furnace by the 20 pusher, the pusher being timed so that the billets are allowed to remain in the furnace a sufficient length of time so that they are thoroughly heated and supplying the rolls with heated billets as rapidly as they can be 25 taken out of the furnace by the rolls. The line of billets extends across the skids where they gradually become heated as they reach the hearth 21. The points of contact of the billets with the skids 19 will not be heated 30 as high as other portions of these billets, for the reason that the skids are water-cooled and the temperature at these points is reduced so that as the billets pass upon the hearth, which is composed of sandstone and 35 extends longitudinally of the furnace, these portions of the billets commonly known as "black spots" will be heated to the same degree as the balance of the billet, so that as the billets pass across the hearth 21 the billet 40 is uniformly heated throughout its entire structure. These billets are pushed upon the discharge skids 25 and 26 formed of heavy steel billets, and are heated to substantially the same temperature as the billets 45 when they reach the skids passing through the heating furnaces. When they reach these skids they are discharged from the heating furnace through the door 24 by a mechanical pusher into the first roll pass, 50 the mechanical pusher being one in common use and not shown in connection with this application. The temperature of the billets on the under side may be slightly reduced from that of the upper side, but this is immaterial for the reason that the upper rolls in the roll pass are usually water-cooled and the hot side of the billets will not stick to these rolls and as the billet enters the rolls the upper side coming in contact with the 55 water-cooled rolls will be reduced in temperature so that as the billet enters the rolls its temperature is substantially uniform throughout and results in the same percentage of elongation being maintained throughout the entire billet without the rough spots 60 65

being formed therein which have been common heretofore.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention. 75

I claim:

1. A hearth for continuous heating furnaces comprising in combination a plurality of sandstone slabs and a pair of discharge skids extending transversely of the said 80 furnace, each of said skids having its edges rounded and extending a slight distance above the level of the hearth's surface.

2. A discharge runway for a continuous heating furnace comprising in combination 85 a pair of members in spaced longitudinal relation with each other extending transversely across the furnace hearth, a plurality of posts supporting the said members and means for securing said posts to the 90 furnace.

3. A runway for heating furnaces comprising in combination a pair of members in spaced longitudinal relation with each other having their upper surfaces rounded and extending above the surface of the hearth, a plurality of posts upon which said members are mounted, means for securing the said runway members to the said posts and 95 means for securing the said posts to the said 100 furnace.

4. A discharge runway for continuous heating furnaces comprising in combination a pair of members in spaced relation with each other and extending transversely across the said hearth, a plurality of posts having V-shaped recesses in their upper ends adapted to support the said spaced members, means for securing the said posts to the 105 said furnace, and means for securing the 110 said runway members to the said posts, the under surface of the said runway members fitting into the said V-shaped recesses of the said posts.

5. A discharge runway for continuous 115 heating furnaces comprising in combination a pair of members in spaced relation with each other and extending transversely across the said hearth, a plurality of posts having V-shaped recesses in their upper ends 120 adapted to support the said spaced members, means for securing the said posts to the said furnace, means for securing the said runway members to the said posts, the under surface of the said runway members fitting 125 into the said V-shaped recesses of the said posts, bolts extending through the ends of said posts and through said skid members, and keys adapted to hold the said skid members in contact with the said posts. 130

6. A discharge runway for a heating furnace comprising a steel billet extending across the said furnace, the said billet having its upper edge rounded and extending below the furnace hearth and means for supporting the billet in the furnace hearth.

7. A discharge runway for heating furnaces, comprising a pair of steel billets in spaced relation with each other extending 10 transversely of the said furnace, means for supporting the billets in the furnace hearth, the said billets having their upper edges rounded, the highest point of said billets extending above the furnace hearth and the 15 edges of the rounded portions extending below the furnace hearth.

8. A continuous heating furnace comprising in combination, skids adapted to support billets, a sandstone hearth adapted to

receive the billets when discharged from 20 said supporting skids, and discharge skids mounted in said hearth, the discharge skids being adapted to be heated to substantially the same temperature as the billets discharged thereover.

25 9. A continuous heating furnace comprising in combination, supporting skids, a sandstone hearth adapted to receive billets when discharged from said supporting skids, and steel billets forming a discharge 30 runway in said hearth, the said billets being heated to substantially the same temperature as the heated billets passing thereover.

35 Signed at Chicago, Illinois, this 29th day of October, 1926.

EARL D. WRIGHT.
